[57] CLAIM

The ornamental design for an aerial toy, as shown and described.

DESCRIPTION

FIG. 1 is a top perspective view of an aerial toy showing my new design;

FIG. 2 is a top plan view thereof;

FIG. 3 is a side elevational view thereof;

FIG. 4 is a bottom perspective view thereof;

FIG. 5 is a perspective view of two members of the design shown unfastened and in an exploded condition; and,

FIG. 6 is a cross-sectional view of one member taken along line VI—VI in FIG. 2.

FIG. 1

FIG. 2

FIG. 3

FIG. 4

FIG. 5
